[57] CLAIM

The ornamental design for a tungsten halogen lamp fixture, as shown and described.

DESCRIPTION

FIG. 1 is a bottom perspective view of a tungsten halogen lamp fixture showing our new design, the broken lines being shown for illustrative purposes only;

FIG. 2 is a top plan view thereof;

FIG. 3 is a front elevational view thereof;

FIG. 4 is a left side elevational view thereof;

FIG. 5 is a bottom plan view thereof;

FIG. 6 is a right side elevational view thereof; and,

FIG. 7 is a side elevational view of a second embodiment of our new design, the second embodiment differing from the first only by the transparency of its globe.

FIG. 1

FIG. 6

FIG. 5

FIG. 2

FIG. 4

FIG. 3

FIG. 7
